PAPER RETAINER

Frederick C. Bartels, Detroit, Mich.
Application March 11, 1937, Serial No. 130,240

1 Claim. (Cl. 45—131)

This invention relates to paper retainers of a type particularly adapted for use with drawing boards and the like.

The tacking of paper or other objects to drawing boards, bulletin boards and the like is highly undesirable because of the punching of holes in the surface thereof. The continuous use of a few sizes of paper creates many tack holes in the surface of a drawing board at various restricted areas thereof. In drafting rooms and places where bulletins are posted, the surfaces of drafting boards and bulletin boards become so pitted from tacking drawing paper, notices and the like thereto that the drawing or bulletin boards must be frequently refinished or replaced at considerable expense. The fewer the sizes of paper used, the quicker the boards wear out from tack holes being punched in the surface thereof.

As drawing boards, bulletin boards or the like become honey-combed with thumb tack holes, thumb tacks will not be firmly retained thereby which causes a loss of thumb tacks and the loosening of paper tacked thereto.

The main object of this invention is to provide means for securing papers and other objects to drawing boards, bulletin boards and the like which will not injure the working surface of the said boards.

Another object of this invention is to provide paper securing means which may be permanently built into drawing boards, bulletin boards and the like.

Another object of this invention is to provide, in combination with a drawing board or the like, means fixed therethrough for securing paper thereon.

Another object of this invention is to provide, in combination with a drawing board or the like, paper securing thumb screws threaded through apertures in the front of said board into anchorage means fixed in the rear thereof, said paper securing screws being replaceable by like screws adapted to fill said apertures and provide a smooth working surface on the front of said board when said paper securing thumb screws are not in use.

Other objects of the invention will become apparent by reference to the following detailed description taken in connection with the accompanying drawing, in which:

Fig. 1 is view in elevation of a drawing board having paper secured thereto by paper securing means embodying the invention.

Fig. 2 is an enlarged sectional view of a preferred embodiment of the invention taken on the line 2—2 of Fig. 1.

Fig. 3 is an enlarged elevational view of one of the paper securing means shown in Figs. 1—5 and 2.

Fig. 4 is an enlarged view part in section and part in elevation of a thumb screw showing the end thereof adapted to be readily and easily upset if and when desired.

Fig. 5 is an enlarged sectional view taken on the line 5—5 of Fig. 1 showing the invention as in Fig. 2 except that the thumb screw has been replaced by a like screw adapted to fill the aperture provided through the drawing board to accommodate said thumb screw.

Fig. 6 is a detailed view part in section and part in elevation of the fill screw shown in Fig. 5.

Referring now to the drawing wherein like numerals refer to like and corresponding parts throughout the several views, the preferred embodiment of the invention shown therein in combination with a drawing board or the like 10 comprises, in general, a nut 11 secured in suitable bore 12 in the rear of said drawing board 10 by such means as the setscrew 13, and a paper securing thumbscrew 14 threaded in said nut 11 from the front of the said board 10 through an aperture 15 therethrough replaceable by a like screw 16 having a firm resilient 30 tapered head 17 which fills said aperture 15 and provides a smooth working surface on the front of said board 10 when said thumbscrew 14 is removed.

The nut 11 is preferably cylindrical in shape and is centrally bored and threaded to accommodate the threaded thumbscrew 14, the outwardly disposed end of said central bore thereof being deeply countersunk at 18 as shown in Figs. 2 and 5. A wood setscrew 13 positioned through the diagonally disposed countersunk bore 19 extending from the countersink 18 through the side of the nut 11 engages the board 10 thereby permanently fixing said nut 11 in the bore 12.

The annular aperture 15 provided through the front of said board 10 is in alignment with and slightly larger than the diameter of the central threaded aperture of the nut 11 into which the thumb screw 14 may be inserted and turned until the head of said thumbscrew 14 is drawn tightly against the paper 20 as shown in Figs. 2 and 3 for fixing said paper 20 to the board 10.

Any number and arrangement of paper securing means may be used, a typical arrangement

being disclosed in Fig. 1 wherein the paper 20 is shown secured to the board 10 by five thumbscrews 14, said paper 20 being the standard size of sheet adopted in the particular instance. If 5 two standard size sheets are adopted, the smaller sheet of paper indicated by the dotted lines 21 in Fig. 1 may be secured to the board 10 by four thumbscrews 14, two of which are shown replaced by the fill screws 16 adapted to fill the 10 aperture 15 through the surface of the board 10 when the larger sheet of paper 20 is being used 15 as indicated in Figs. 1 and 5.

Wherever the thumbscrews 14 need never be removed, as for example, the thumbscrews 14 15 around the periphery of the largest standard size drawing paper adopted, the ends thereof may be upset by peening as indicated by the dotted lines 22 in Fig. 2 to prevent their removal from the board 10. In order to permit said upsetting 20 without possibly splitting the surface of the board 10 above the nut 11, the end of the thumbscrew 14 is countersunk to a feather edge as indicated by the numeral 23 in Fig. 4. The head of said thumbscrew 14 is preferably as flat as possible 25 and formed to a feather edge to admit a T-square or triangles to slide over the same, the top of said head thereof being suitably knurled as at 24 to permit said thumbscrew 14 to be turned by frictionally engaging said head thereof 30 by the thumb or finger of the user thereof.

The fill screw 16 as best shown in Fig. 6 comprises a threaded shank having the end portion thereof knurled as at 25 to permit the same to be readily gripped for turning and adjusting. 35 The top of said fill screw 16 is headed as indicated by the numeral 26 over which a tapered stiff yet slightly compressible rubber head 17 is disposed, said rubber head 17 being cemented or otherwise retained on the head 26 of said fill 40 screw 16.

When the fill screw 16 is positioned through the annular aperture 15 in the board 10 and

threaded in the nut 11, the knurled end 25 of said fill screw 16 extending into the countersink 18 of the nut 11 may be gripped by the user's fingers and turned to accurately level the top of the tapered head 17 thereof with the working 5 surface of the drawing board 10.

It will be noted that the thumbscrews 14 are so positioned in the board 10 as to engage the paper 20 thereunder without puncturing the same, thereby permitting paper to be secured 10 and removed from the said board as many times as desired without perforating the same. The invention admits of the use of as large diameter thumbscrew heads as may be required to properly hold the paper or other objects to the board, 15 prevents destruction of the board or paper secured thereto because of honey-combing or perforating the same, and provides means for surfacing the board if desired when thumbscrews 20 are not in use.

Although but one embodiment of the invention has been disclosed and described herein, it will be understood that various changes including the size, shape, arrangement and details of the various parts thereof may be made without departing 25 from the spirit of the invention, and it is not intended to limit the scope of the invention other than by terms of the appended claim.

I claim:

In combination with a drawing board or the like, 30 paper securing means comprising a nut centrally bored and threaded positioned wholly within said board in a suitable bore in the rear thereof, the exposed end of said nut being countersunk, a diagonally disposed setscrew extending through 35 said nut from the countersunk surface thereof into said board, said board having an aperture through the front thereof communicating with said threaded nut, and a thumbscrew for securing paper to the front of said board threaded in 40 said nut.

FREDERICK C. BARTELS.
